UNITED STATES PATENT OFFICE.

JAMES HOULEHAN, OF TOLEDO, OHIO, ASSIGNOR OF ONE-HALF TO
RATHBUN FULLER, OF SAME PLACE.

UNLOADING PLATFORM-CARS.

SPECIFICATION forming part of Letters Patent No. 293,467, dated February 12, 1884.

Application filed December 14, 1883. (No model.)

To all whom it may concern:

Be it known that I, JAMES HOULEHAN, of Toledo, in the county of Lucas and State of Ohio, have invented certain Improvements in 5 Devices for Unloading Platform-Cars, of which the following is a specification, reference being had to the accompanying drawings, and to the letters of reference marked thereon.

My invention has reference to a machine or 10 device for unloading gravel or other material from ordinary platform-cars, and is designed to accomplish the unloading of the whole contents or one-half of the contents of the car. The arrangement is such that the gravel or 15 other material may by one adjustment be unloaded from both sides of the car simultaneously, one-half being thrown to each side; or by another adjustment one half may be thrown from one side, the other half being retained 20 on the car; or by a third adjustment the entire load may be thrown from the right side of the car, and by a fourth adjustment the whole load may be thrown from the left side of the car.

25 In the accompanying drawings, forming a part of this specification, Figures 1, 2, and 3 are plan views, illustrating my improved unloading device arranged in different positions on a platform-car. Fig. 4 is a side view, and 30 Figs. 5 and 6 are front views, of my improved unloading device.

Similar letters of reference indicate similar parts in the respective figures.

A is the central timber, running or extending 35 longitudinally of the unloader, and carrying at its upper side the transverse beams B, and on its under side suitable shoes shaped to fit over the rail E, secured on the car for guiding the unloader. To the transverse beams B 40 are secured the side beams, C.

D is a nose-casting rigidly secured at the forward end of the central timber, A, of the unloader by any suitable means. The under side of the nose-casting D is grooved or shaped 45 to fit over the rail E.

F are the sides or wings of the unloader, constructed of metal or other material, and braced or re-enforced in any known manner. These sides or wings F are hinged to the 50 under or outer sides of the side beams, C, as

shown at f, so that said wings can be readily detached from the beams C.

The nose-casting D is made narrow, as shown, and provided with a hinge, G, having bolts g or other suitable connecting devices located 55 on the lower forward end of each wing F.

As shown in Fig. 1, the forward movement of the device along the rail E effects the unloading of the entire contents of the car, one-half being discharged from each side. The 60 elevation of either of the wings F, which is accomplished by hand, will adjust the unloader for discharging one-half the load from one or the other side of the car, as the case may be.

To prepare for the removal of the whole load 65 from one side of the car, as shown in Fig. 2, the wing at the left of Fig. 1 is moved pivotally on the hinge G to the position shown in Fig. 2, in which position the wing is rigidly retained by means of braces H, which connect 70 the rear face of the wing with the beam C thereof. The other wing is adjusted in a similar way, to effect the discharge of the whole load from the other side of the car, as shown in Fig. 3. A triangular block, I, is placed in 75 the opening or gap formed between the adjacent ends of the two wings when either one or the other is swung around. This triangular block is made to conform to the shape of the wings, and retained in position by suitable 80 means. Thus it will be seen that my invention is capable of ready adjustment to effect the various discharging operations.

This unloader is simple, strong, and effective 85 in action.

I do not confine my invention to the particular mode of pivoting the wings herein described, nor to any special mode of bracing.

I claim as my invention—

1. The combination, in an unloading device, 90 of one or more wings horizontally or laterally movable, substantially as set forth.

2. The combination, in an unloading device, 95 of one or more wings horizontally or laterally moving upon a pivot or pivots, substantially as described.

3. The combination, in an unloading device, 100 of one or more horizontally or laterally moving wings pivoted at its or their forward ends, substantially as described.

4. The combination, in an unloading device, of one or more horizontally or laterally and vertically moving wings, substantially as described.
  5. The combination, in an unloading device, of wings, one of which is adapted to be swung on a line with the other wing, substantially as set forth.
  6. The combination, in an unloading device, of one or more horizontally or laterally moving wings and one or more braces, substantially as described.
  7. The combination, in an unloading device, of wings F F and devices or connections for securing one of said wings on a line with the other wing, substantially as described.
  8. The combination, in an unloading device, of one or more horizontally or laterally and vertically moving wings and detachable con-
- nections permitting such movements of the 20 wing or wings, substantially as set forth.
9. The combination, in an unloading device, of wings, one of which is adapted to swing on a line with the other wing, and a filling block or brace designed to be inserted between and 25 brace the adjoining ends of the said wings, substantially as set forth.
10. The combination, in a device for unloading, of a nose provided with a hinge, and wings pivoted thereto, substantially as set forth. 30
- In testimony whereof I have hereunto set my hand and seal this 24th day of November, A. D. 1883.

JAMES HOULEHAN. [L. S.]
